CLAIM

The ornamental design for a wood splitter, as shown and described.

DESCRIPTION

FIG. 1 is a perspective view of a wood splitter showing our new design;

FIG. 2 is a left-hand side elevational view thereof, with the right-hand side elevational view being substantially identical;

FIG. 3 is a front elevational view thereof, with the rear elevational view being substantially similar;

FIG. 4 is a top end view thereof;

FIG. 5 is a bottom view thereof; and

FIG. 6 is an enlarged and fragmentary side elevational view of a portion of the handle thereof, as shown more fully in FIG. 2.

Fig. 6.

Fig. 1.

Fig. 2.

Fig. 3.

Fig. 4.

Fig. 5.
